UNITED STATES PATENT OFFICE.

FRANK MARCOVSKY, OF PITTSBURGH, PENNSYLVANIA.

PROTECTIVE ARMOR FOR CYCLE-RIDERS.

1,144,150.

Specification of Letters Patent. Patented June 22, 1915.

Application filed August 5, 1914. Serial No. 855,249.

To all whom it may concern:

Be it known that I, FRANK MARCOVSKY, a citizen of the Empire of Russia, residing at Pittsburgh, in the county of Allegheny and 5 State of Pennsylvania, have invented certain new and useful Improvements in Protective Armor for Cycle-Riders, of which the following is a specification.

My invention relates to improvements in 10 flexible protective armor, and is particularly adapted for use by motor-cycle riders.

The objects in view are to provide a protective armor or suit having sufficient flexibility to permit of free and unhampered use 15 of the limbs, together with an outer series of projecting pneumatic tubes or cushions capable of inflation.

One preferred embodiment of the invention is illustrated in the accompanying 20 drawings, in which—

Figure 1 is a front view in elevation of the complete suit, including the helmet or head piece. Fig. 2 is a rear view in elevation, the helmet being removed. Fig. 3 is a 25 vertical sectional view through the head piece, indicated by the line III. III. of Fig. 4. Fig. 4 is a horizontal sectional view through the head piece, indicated by the line IV. IV. of Fig. 1 and Fig. 3. Fig. 5 is a 30 detail view in perspective of the metallic protecting coping of the upper portion of the head piece. Fig. 6 is a similar view of the supporting frame for the head piece. Fig. 7 is a detail view, enlarged, showing a 35 portion of one of the pneumatic tubes and its incorporation with the fabric of the suit. Fig. 8 is a sectional view, indicated by the line VIII. VIII. of Fig. 7.

The suit in its entirety comprises a one-piece garment, having the body, legs and arms, and a detachable helmet or head piece, each of such portions being provided with 40 inflatable cushioning elements adapted to be filled with compressed air, for the purpose 45 of protecting the wearer from shocks or blows incidental to accidents or the use to which the armor is put.

The suit proper is of one piece of fabric, 50 suitably cut to conform to the shape of the body, and sewed together, providing the body portion 2, the arms 3, 3, and the legs 4, 4. The suit is made of suitable material, as canvas, or other strong fabric, and is divided vertically, either at the front or 55 back, by a parting opening 5, each edge hav-

ing a series of lacing holes or buttons, whereby it may be tightly laced together by the lacing indicated at 6, for the purpose of putting on and off by the wearer. The body portion of the suit is covered at the front 60 and back by a series of pneumatic tubes 7, of rubber or other suitable material, laid upon the fabric 2 of the suit, and inclosed within embracing flaps 8, 8, which surround the tube and which are laced together by 65 laces 9 in the same manner as the suit itself is held together, whereby the tubes 7 are embraced on the outermost portion of the suit and protected, and provided for easy insertion or removal. The tubes as thus in- 70 cased, and with the enveloping fabric, thus constitute series of vertically arranged inflatable ribs 10, running up and down along the back of the suit, as indicated in Fig. 2, carried over the shoulders, and then up and 75 down the front, terminating in closed ends adjacent to the laced divisional slit 5, as in Fig. 1. The arms 3 are covered in a similar manner by inflatable ribs 11, which are laid back and forth across the outer portions 80 of the shoulders, and below the arm pits wound around the arms, terminating at the wrists, as shown. The front faces of the leg members 4 above the knee are covered by similar inflatable ribs 12, running back and 85 forth across the upper portion of the leg above the knee, and at and below the knee being wound around the leg in the same manner as with the arms, thereby completely 90 protecting the front lower portions of the leg sections, leaving the rear seat portion free. Each of such several inflatable rib portions is provided at any suitable point 95 with a terminal connection 13 of well-known nipple construction, provided with a check valve, for inflation of the tubular ribs by an air pump, as will be readily understood, such connection being at readily available points, and whereby the several continuous protecting ribs may be inflated to the 100 necessary pressure for providing the desired pneumatic cushioning effect. As thus arranged, it will be seen that the several parts of the armor are entirely flexible, the limb members being free from interference, and 105 whereby the wearer has full use of his limbs.

The helmet or head piece is composed of a rounded dome-like head-inclosing hood, the outer portion of which is of rubber or other suitable material having continuous 110

outer and inner walls 14, 15, respectively, with an intervening air cavity 16, a sight opening 17 being provided at the front for the eyes or face of the wearer, the lower portion being preferably looped at the front and connected in any suitable manner, as indicated at 18, for convenience in attachment and detachment. The inner portion of the helmet is lined with an inclosing wall of 5 cushioning material 19, as felt or other suitable substance, and the lower portion of the helmet and the sight opening is formed by end walls 20 of the outer inflatable hood. A suitable nipple 21 is also provided at a convenient location for connection with an air 10 pump. The lower portion of the helmet, as thus made, is curved, as indicated at 22, whereby to seat upon a supporting cushion 23, which is affixed to and encircles the 15 upper portion of the main armor, clearly shown in Figs. 1 and 2, for supporting the helmet. Within the helmet, for the purpose of giving it rigidity and protective strength, is mounted a metallic frame, as shown in 20 Fig. 6. This frame is composed of a base 24, preferably composed of two U-shaped pieces of flat metal, preferably hinged together, as indicated at 25, 26, whereby it may be readily disconnected at one of such joints and 25 opened for removal from the head with the helmet itself. The base 24 as thus constructed is also provided with suitable attaching apertures 27, whereby it may be fixedly connected by holding buttons 28, 30 with the supporting cushion 23, such buttons being of well-known construction, and similar to those used with automobile curtains for connection and disconnection by one-quarter turn. The upper portion of the 35 helmet is provided with the protecting coping shown in Fig. 5. This consists of a flat ring 29, which is set in the inner upper portion of the helmet, and is provided with a series of upwardly arched strips 30 of suitable light, strong material, as bamboo, etc., 40 riveted to the ring 29, as indicated at 31, whereby to provide a comparatively light upwardly arching bracing support for the crown of the helmet. The ring 29 and its 45 upper portion as thus made is permanently incorporated in the helmet between the wall 15 and the cushion 19, as indicated in Fig. 3. The support 24 is provided with a plurality of upwardly extending diverging arms 32, 50 fixedly connected with the base 24 and adapted to project upwardly through suitable receiving spaces 33 within the helmet between the inner cushion 19 and wall 15, and to abut against the underside of ring 29, as indicated in Fig. 3. By this construction the helmet itself is comparatively strong, well cushioned, and amply protective, and is supported in position above the 55 main suit in such a manner as to give it ample strength and positioning function,

while readily allowing for attachment or removal, and for ample convenience to the wearer in giving a free passage for the head and neck, and an outlook and breathing opening in the front.

The fabric of the suit is provided with numerous perforating ventilating openings 70 30 whereby to provide for air supply, and also assisting in the flexibility of the suit.

The construction, advantages and utility 75 of the invention will be readily understood from the foregoing description, and will be appreciated by those accustomed to the use of motor-cycles or other high speed dangerous vehicles.

All exposed portions of the body of the 80 wearer are amply protected against severe shocks of impact or blows incidental to accidental contact with the ground, other riders, fences, etc.

The suit is comparatively light, amply 85 flexible, and of comparatively simple and inexpensive construction. It may be changed or varied in the arrangement of the tubular ribs, their manner of application, the detail 90 construction of the several parts, or otherwise by the skilled mechanic, but all such changes are to be considered as within the scope of the following claims.

What I claim is:—

1. An armor suit consisting of continuous 95 flexible fabric and provided with outermost series of tubular ribs, individual separable casings therefor secured to the fabric, substantially as set forth.

2. An armor suit consisting of continuous 100 flexible fabric and provided with outermost series of tubular ribs arranged in looped arrangement, individual separable casings therefor secured to the fabric, substantially 105 as set forth.

3. An armor suit consisting of continuous 110 flexible fabric and provided with outermost series of tubular ribs arranged in looped arrangement across the body, shoulder and thigh portions, and encircling the terminal portions of the arms and legs, substantially as set forth.

4. The combination with a suit of suitable fabric, of an outermost protecting inflatable tube of suitable material variously arranged thereon and provided with an inflating terminal connection, and a divisible laced casing therefor secured to the fabric, 115 substantially as set forth.

5. The combination with the suit fabric, of an inflatable tube, and supplemental inclosing flaps therefor secured to the suit and having means for connecting them together around the tube, substantially as set forth.

6. The combination with a suitable divided continuous one-piece suit, of series of inflatable conduits laid upon the body portion, arms and legs of the suit, each of such series being provided with an air pressure 120 125 130

connection, and with a divisible laced casing secured to the fabric, substantially as set forth.

7. The combination with a suit of the class described provided with a neck opening and a two-part separable supporting base encircling the neck opening, of a superimposed helmet having an inner supporting frame removably connected with the suit, substantially as set forth.

8. The combination with a suit of the class described provided with a neck opening and a two-part separable supporting base encircling the neck opening, of a superimposed helmet having an inner supporting frame removably connected with the suit and separable from such support, substantially as set forth.

9. The combination with a suit of the class described having a neck opening, of a two-

part separable supporting frame mounted thereon extending upwardly above the neck opening and provided with a series of arms, and a surrounding helmet having an outer cushioning portion and receiving apertures 25 for said frame, substantially as set forth.

10. The combination with a suit of the class described, of a helmet consisting of an outer inflatable portion, and an inner cushioning portion, an upper protecting coping, 30 a two-part separable neck ring, and a supporting frame extending upwardly from said ring within the helmet and engaging the said coping, substantially as set forth.

In testimony whereof I hereunto affix my 35 signature in the presence of two witnesses.

FRANK MARCOVSKY.
